APPARATUS FOR COATING PLATES

Ernest Penker, Flushing, and Martin Bulin, Jackson Heights, N. Y., assignors to Etched Products Corporation, Long Island City, N. Y., a corporation of New York

Application October 10, 1947, Serial No. 778,998

8 Claims. (Cl. 91—50)

1

This invention relates to coating apparatus, and more particularly, to apparatus for coating one surface of a metal plate which is to be dipped in an etching bath.

In preparing a metal plate for etching—for example, to provide raised characters on its surface—the characters are imprinted on one surface of the plate by a suitable ink. The ink is then protected by a suitable material resistant to the action of the chemicals in the etching bath. The opposite surface of the plate is coated with asphalt or other material resistant to the chemical action of the etching solution.

After the coatings have dried, the plate is placed in the etching solution. The solution attacks only the uncoated portions of the metal. As a result, the surface of the metal around the characters is dissolved, leaving raised characters on the plate surface. The height of the characters is determined by proper correlation of the strength of the etching solution and the time interval of immersion.

It is important that the metal surface to be etched be clean. Consequently, it is necessary not to touch this surface with the fingers, as the oily deposit resists the action of the etching solution. Likewise, the coating of the back surface of the plate should not be touched until it is thoroughly dry. Apparatus for handling and coating such plates has hitherto not been satisfactory from the standpoint of these two conditions.

In accordance with the present invention, a coating apparatus, for coating the back surface of the plate, is provided in which the front surface need not be handled and the back coating is not touched until thoroughly dried. The plate, having the characters printed thereon and coated, is handled through its back surface and placed on a roller conveyor mechanism. This mechanism feeds the plate in contact with a coating roller from which the plate is discharged onto a conveyor which engages only the lower corners of the longitudinal edges of the plate.

Roller means are provided to press the back surface of the plate against the coating rollers. In such roller means were aligned with the coating roller, it would become smeared with the coating material and correspondingly smear the front surface of the plate. Accordingly, the present invention utilizes two pressure roller means, one in advance of the coating roller and the other rearwardly thereof.

The forward roller presses the plate against the coating roller when the first portion of the

2

plate passes the coating roller. The rear pressure roller is mounted for movement into and out of engagement with the plate. An automatic scanning device, such as an "electric eye" is provided which, when the leading plate edge approaches the coating roller, actuates mechanism to retract the rear pressure roller. When the trailing edge of the plate passes the scanning mechanism, the rear pressure roller is engaged with the plate.

The receiving conveyor comprises longitudinally spaced pairs of rollers having their axes angularly disposed to form a V bisected by a perpendicular to the plate surface. Thus, these rollers engage only the lower corners of the side edges of the plate. The rollers are further formed with axially spaced, circumferential grooves receiving such corners. With this constructional arrangement, the coated under surface of the plate is not contacted until it has had a chance to thoroughly dry.

The receiving conveyor as a whole is made vertically adjustable so that the horizontal spacing between the rollers, at the plane of movement of the plate over the coating roller, will substantially equal the width of the plate. This assures contact between the longitudinal plate edges and the conveyor rollers. To facilitate this vertical adjustment, a feeler gauge is provided on the feeding conveyor means for accurately centering the plate thereon and has a scale carrying plate width indicia. A similarly marked scale is associated with the vertical adjustment means for the receiving conveyor, so that the latter's height is adjusted in accordance with the plate width.

It is accordingly an object of this invention to provide novel apparatus for coating a surface of a metal plate.

Another object is to provide a novel plate receiving conveyor having support means contacting only the lower corners of the longitudinal edges of the coated plate.

A further object is to provide automatically operative pressure means, spaced from the coating means, and engaged with the plate responsive to the position thereof relative to the coating means.

A still further object is to provide a novel arrangement for accurately adjusting the height of the receiving conveyor in accordance with the plate width.

These, and other objects, advantages and novel features of the invention will be apparent from

the following description and the accompanying drawings. In the drawings:

Fig. 1 is a side elevational view of apparatus embodying the invention.

Fig. 2 is a plan view of the apparatus shown in Fig. 1.

Fig. 3 is an elevational view, partly broken away, of a detail of the apparatus.

Fig. 4 is a sectional view on the line 4—4 of Fig. 3.

Fig. 5 is a central longitudinal sectional view of the apparatus, on the line 5—5 of Fig. 2.

Fig. 6 is a front elevational view of the apparatus, partly broken away to illustrate certain details more clearly.

Fig. 7 is a sectional view on the line 7—7 of Fig. 6.

Fig. 8 is a sectional view on the line 8—8 of Fig. 7.

Fig. 9 is an elevation view partly in section, on the line 9—9 of Fig. 8.

Fig. 10 is a medial transverse elevational view taken substantially on the line 10—10 of Fig. 1.

Fig. 11 is a sectional view on the line 11—11 of Fig. 10.

Figs. 12 and 13 are sectional views on the correspondingly numbered lines of Fig. 11.

Fig. 14 is a rear elevation view of the apparatus, showing a coated sheet receiving conveyor in one position.

Fig. 15 is a view, similar to Fig. 14, showing the conveyor in another position.

Figs. 16 and 17 are somewhat diagrammatic views illustrating certain features of the operation of the invention.

Referring to the drawings, the coating apparatus of the invention is mounted on a suitable frame generally indicated at 18, and includes conveyor mechanism 20 for feeding a sheet 30 to be coated, into contact with a coating roller 40. Coating roller 40 applies a coating of asphalt, or of other material resistant to the chemicals of the etching bath, to the underface of sheet 30. A conveyor 50 receives the coated sheet as it passes from coating roller 40, and is so arranged that it engages the sheet only on the lower corners of the longitudinal or side edges of the sheet. A pressure roller 60 is disposed in advance of roller 40 for pressing sheet 30 firmly against the coating roller during the passage of the forward portion of the sheet over the coating roller. When substantially half the sheet has passed coating roller 40, a series of rollers 70 disposed rearwardly of roller 40 engage the sheet to hold it in contact with roller 40.

Rollers 70 are moved between a retracted and an engaged position with respect to sheet 30 by suitable means which is hereindicated as two air cylinder arrangements 80. Admission of air to air cylinders 80 is controlled by an air valve which is in turn under the control of a photoelectric scanning device generally indicated at 90. As the forward edge of sheet 30 passes beneath scanning device 90, air cylinders 80 are activated to move rollers 70 to the retracted position. When the rear or trailing edge of sheet 30 passes beneath scanning device 90, air cylinders 80 are again activated to move rollers 70 into engagement with sheet 30. This causes arms 70 to press sheet 30 against roller 40 during passage of the rear half of the sheet past the roller.

The sheet feeding conveyor mechanism 20 includes a plurality of rollers 21 which are journaled in side frame members 22, 22. Each roller

21 has a sprocket 23 affixed to one end of its central shaft 24, and a chain 26 extends over these sprockets and over a sprocket 41 on the shaft 42 of coating roller 40. A slack take-up means is provided in the form of a sprocket 27 mounted in bearing 28 on rod 29. Rod 29 extends through bracket 31 and has a threaded end to which is secured a nut 32 for adjusting the tension of chain 27 by setting the longitudinal position of rod 29.

The driving mechanism includes a motor 25 having a speed changing pulley 33 connected by a belt 34 to drive a pulley 36 of a gear reduction unit 35. Gear reduction unit 35 has a shaft 37 extending rearwardly therefrom and provided with a bevel gear 38 which meshes with a bevel gear 39 secured to a shaft 43 rotatably mounted in an arm 44 secured to a column 46 of frame 18. Shaft 43 has a sprocket 47 on its outer end which, through a chain 48, drives a sprocket 49 on the shaft 51 of a roller 45, having a function described hereinafter. Roller 45 is provided with a spur gear 52 meshing with a spur gear 53 on roller 40. Thus, through the described arrangement, motor 25 rotates rollers 21. The chain 26, intermediate sprockets 23, is held in engagement with the roller sprockets by idling sprockets 54 mounted in the frame members 22.

Roller 45 has substantial surface contact with coating roller 40 to apply the coating material thereto. This material is preferably asphalt or other material resistant to the chemicals of the etching bath. The coating material is in a tank 55 which is supported on spaced pairs of interconnected links 56 pivoted on frame members 57. A handle 58 is secured with a shaft secured to the forward links, whereby tank 55 may be adjusted vertically by swinging the links 56. Tank 55 may be refilled through a filling neck 59 at its forward end.

Roller 45 is adjustably mounted to assure proper application of the coating material to coating roller 40. The adjustable mounting arrangement is best shown in Figs. 6 through 9 as comprising a pair of forked arms 61 pivoted on pins 62 set in vertical frame members 63. Shaft 51 of roller 45 extends through arcuate slots 64 in members 63 and sets in bushings 66 in the forked ends of arms 61. The opposite ends of arms 61 are provided with brackets 67 engaged by studs 68, threaded through brackets 71 on frame members 22 and provided with lock nuts 72. Adjustment of studs 68 swings arms 61 to adjust roller 45 relative to roller 40 and tank 55. The adjustment is locked by studs 73 extending through arcuate slots 74 in arms 61 and threaded in member 63.

A feature of the invention is the use of a plate centering gauge on feeding conveyor means 20. This gauge 75 comprises flat plate 76 mounted for transverse movement in guides 77 and carrying fingers 78 for engaging a longitudinal edge of plate 30. One guide 77 is provided with a clamping means 79 for retaining plate 76 in adjusted position. A scale 81 on plate 76 is graduated in plate widths and cooperates with a pointer 82 on a guide 77. When pointer 82 indicates the plate width on scale 81, fingers 78 position plate 30 centrally of conveyor means 20. As will be explained hereinafter, gauge 75 has a functional cooperation with a height gauge on receiving conveyor 50.

An important feature is the pressure rollers 60 and 70, for pressing plate 30 firmly against the coating material on roller 40. If pressure rollers

were vertically aligned with roller 40, considering the relative thinness of plate 30, the pressure rollers would pick up coating material from roller 40. In pressing plate 30 against roller 40, the pressure roller would smear coating material on the upper surface of plate 30 carrying the coated, printed characters. Consequently, in the present invention, forward and rearward pressure rollers 60 and 70 are provided, which are not vertically aligned with roller 40.

Forward pressure roller 60 has its shaft 86 carried in bearings 87 which are mounted on the lower ends of studs 88 threaded through ears 89 on a frame member 91. By adjustment of studs 88, the distance between rollers 40 and 60 may be regulated in accordance with the thickness of plate 30. Roller 40 is driven, by a chain 201, from roller 45.

The rear rollers 70 are arranged to be moved from a plate engaging position to a retracted position in accordance with the travel of plate 30. For this purpose, the axle 92 (Figs. 3 and 4) carrying rollers 70 is mounted in journals 93 set in guides 94 and biased upwardly by springs 96. Studs 97 connect journals 93 to a cross bar 98, to which are secured the piston rods 99 of a pair of air cylinders 80 mounted on brackets secured to the rearward portion of plate 91a.

When air is admitted to cylinders 80, rollers 70 are forced into engagement with the upper surface of plate 30.

Control of the air supply to cylinders 80 is effected by a solenoid air valve 102 supplied with air from a conduit 103 connected to a pressure regulator 104, having a pressure gauge 106, and supplied with air from a suitable source through conduit 107. Conduits 108, 109 connect valve 102 to cylinders 80.

Operation of valve 102 to admit air to or exhaust air from cylinders 80 is under the control of a scanning device such as a photoelectric cell 90. Cell 90 is connected electrically to suitable mechanism in a housing 101, which mechanism controls energization of solenoid air valve 102 in accordance with signal impulses from photoelectric cell 90. As will be explained hereinafter, when the forward edge of plate 30 interrupts the beam on cell 90, valve 102 is actuated to release air from cylinders 80. Springs 96 move journals 93 upwardly to move rollers 70 to the retracted position. When the plate 30 passes from beneath cell 90, the latter acts to cause valve 102 to admit air to cylinders 80, forcing rollers 70 to engage the upper surface of plate 30 and hold the plate against roller 45.

One of the most important features of the invention is the conveyor 50 which receives the coated plates 30 as they are discharged from the coating roller 45. This conveyor comprises a frame 110, mounted for vertical adjustment on frame 18, and spaced pairs of rollers 120 each pair having their axes forming an upwardly opening V bisected by a perpendicular to the surface of plate 30.

Frame 110 includes a base 111 having uprights 112 at its corners connected by upper longitudinal members 113 having their surfaces perpendicular to the axes 114 of rollers 120. Extending centrally of base 111 is an inverted, V-shaped bracket 115. Referring to Figs. 14 and 15, the upper ends of axes 114 are journaled in members 113, and the lower ends in bracket 115. Inside bracket 115, each axle 114 has fixed thereto a sprocket 116.

Chains 117 interconnect all of the sprockets 116

so that all of the rollers 120 will be rotated in unison. For the purpose of driving the rollers, the forward pair of rollers having intermeshing bevel gears 118, one of which meshes with a bevel gear 121. Gear 121 is secured to a shaft 122 in a bearing 123 on a plate 124 extending downwardly from bracket 115.

Shaft 122 is driven from gear reduction unit 35. For this purpose, shaft 37 extends rearwardly through gear 38 and continues as a shaft 126 through a sleeve 127 mounted in a block 128 secured between support 40 and an angular member 129. At its rear end, sleeve 127 has a U-shaped bracket 130 secured thereto by a set screw 131, so that sleeve 127 acts as an axis of oscillation for bracket 130 by virtue of its bearing in block 128.

The rear end of shaft 126 has keyed thereto a bevel gear 133 meshing with a bevel gear 123. Gear 133 is keyed to a shaft 134 mounted in bearings 136 in the arms of bracket 130. Shaft 134 is slidable through gear 133, and a spacing sleeve 137 extends between one bearing 136 and gear 133. One element 138 of a universal coupling is secured to the upper end of shaft 134 and the other coupling element 139 is secured to shaft 122. Rollers 120 are thus rotated by prime mover 25 through a coupling permitting vertical adjustment of rollers 120.

As stated, receiving conveyor 50 is vertically adjustable to receive plates 30 of varying widths and support them in the plane of discharge from coating roller 40. Frame 110 has support and guide columns 141 extending through bearings 142 on supports 143 forming part of frame 18.

A pair of links 144 pivoted on frame 110 and a pair of links 146 pivoted on frame 18 have their adjacent ends pivotally connected to the ends of a bar 147. Similarly, another pair of links 151 pivoted on frame 110 and a corresponding pair 152 pivoted on frame 18 have their inner ends pivotally connected to the ends of a bar 153. Bars 147 and 153 are provided with threaded apertures which receive reversely directed threaded portions 154 on a shaft 154 rotated by hand wheel 155. When shaft 154 is rotated in one direction, the links are pulled toward alignment, raising conveyor 50. Rotation in the opposite direction lowers conveyor 50. The sliding shaft 134 and the universal coupling 138, 139 provide for driving of rollers 120 by motor 25 in any position of conveyor 50.

The operation of the apparatus will be understood best by reference to Figs. 14 through 17. Referring to Figs. 16 and 17, sheet 30, having characters printed and coated on its upper surface, is placed on conveyor 20. Rollers 21 pull sheet 30 toward roller 40. As the forward sheet edge interrupts the beam of cell 90, valve 102 is operated to discharge air from pistons 80 so that springs 96 move rollers 70 to the retracted position. Pressure roller 60 forces the under surface of plate 30 against roller 40, to coat the under surface with asphalt or the like, during passage of the forward part of plate 30 past roller 40.

As plate 30 emerges from roller 40, the lower corners of its side edges are engaged in grooves 156 of rollers 120 of conveyor 50, thus avoiding roller contact with the coated under surface of plate 30. For this purpose, rollers 120 are provided with axially spaced, circumferential grooves 156 receiving the lower side edge corners. As the rear edge of plate 30 passes from beneath cell 90, valve 102 is operated to admit air to cylinders 101, thus pressing rolls 70 against the upper sur-

face of plate 30. This holds the plate against roller 40 during passage of the rear half of the plate in contact with the coating roller.

If rolls 70 were continuously in the lower position, they would bend plate 30 so that it would not properly engage rollers 120 of conveyor 50. The conveyor 50 is vertically adjustable so that the horizontal distance between rollers 120 at the level of plate 30 is equal to the plate width. A gauge 157 on frame 18, cooperable with an indicator 158 on frame 110 may be used to adjust conveyor 50 in accordance with the reading of centering gauge 15 on feeding conveyor 20. Adjustment is made by turning shaft 154 through wheel 155.

The described apparatus thus provides a novel arrangement for coating the imprinted surface of a plate to be etched in a chemical bath. The pressure means for forcing such surface against the coating roller are not aligned with such roller. Consequently, they will not become smeared with the coating material and will, accordingly, not smear the printed surface of the plate. The novel, adjustable, V-roller receiving conveyor engages only the lower corners of the side edges of the plate, so that damage to the coating of the under surface is prevented during drying and hardening thereof. Additionally, novel gauge means are provided to center the plates transversely of the apparatus and to set the height of the receiving conveyor in accordance with plate width.

While a specific embodiment of the invention has been shown and described in detail, to illustrate the application of the principles thereof, it will be understood that the invention may be otherwise embodied without departing from such principles.

What is claimed is:

1. In apparatus for applying a coating to the under surface of a sheet of material, a rotatable coating roller arranged to engage such surface and apply a coating thereto; mechanism for feeding the sheet into engagement with said coating roller; and a conveyor for receiving the coated sheet from said roller, said conveyor including opposed angularly disposed sheet support rollers for engaging only the lower corners of the longitudinal edges of the sheet.

2. In apparatus for applying a coating to the under surface of a sheet of material, a rotatable coating roller arranged to engage such surface and apply a coating thereto; mechanism for feeding the sheet into engagement with said coating roller; and a conveyor for receiving the coated sheet from said roller, said conveyor including longitudinally spaced pairs of sheet supporting rollers, the rollers of each pair being arranged with their axes forming an upwardly opening V bisected by a perpendicular to the center line of the sheet, and engaging only the lower corners of the longitudinal edges of the sheet.

3. In apparatus for applying a coating to the under surface of a sheet of material, a rotatable coating roller arranged to engage such surface and apply a coating thereto; mechanism for feeding the sheet into engagement with said coating roller; and a conveyor for receiving the coated sheet from said roller, said conveyor including longitudinally spaced pairs of sheet supporting rollers, the rollers of each pair being arranged with their axes forming a V bisected by a perpendicular to the center line of the sheet, and engaging only the lower corners of the longitudinal edges of the sheet; each roller having

axially spaced, circumferential grooves receiving such lower sheet corners.

4. In apparatus for applying a coating to the under surface of a sheet of material, a rotatable coating roller arranged to engage such surface and apply a coating thereto; mechanism for feeding the sheet into engagement with said coating roller; a conveyor for receiving the coated sheet from said roller, said conveyor including longitudinally spaced pairs of sheet supporting rollers, the rollers of each pair being arranged with their axes forming a V bisected by a perpendicular to the center line of the sheet, and engaging only the lower corners of the longitudinal edges of the sheet; and means for adjusting said conveyor vertically, in accordance with the sheet width, to receive the sheet in the plane of movement past said coating roller.

5. In apparatus for applying a coating to the under surface of a sheet of material, a rotatable coating roller arranged to engage such surface and apply a coating thereto; conveyor mechanism for feeding the sheet into engagement with said coating roller; a conveyor for receiving the coated sheet from said roller, said conveyor including longitudinally spaced pairs of sheet supporting rollers, the rollers of each pair being arranged with their axes forming a V bisected by a perpendicular to the center line of the sheet, and engaging only the lower corners of the longitudinal edges of the sheet; means for adjusting said conveyor vertically, in accordance with the sheet width; a gauge cooperable with said conveyor means to center the sheet laterally thereof and including indicia correlated with the sheet width; and a scale associated with said conveyor adjustment means and having indicia correlated with the sheet width; whereby said scale may be used in cooperation with said gauge to adjust said device to set the height of said conveyor to receive the sheet in the plane of movement past said coating roller.

6. In apparatus for applying a coating to the under surface of a sheet of material, a rotatable coating roller arranged to engage such surface and apply a coating thereto; mechanism for feeding the sheet into engagement with said coating roller; a conveyor for receiving the coated sheet from said roller, said conveyor including longitudinally spaced pairs of sheet supporting rollers, the rollers of each pair being arranged with their axes forming a V bisected by a perpendicular to the center line of the sheet, and engaging only the lower corners of the longitudinal edges of the sheet; means for adjusting said conveyor vertically, in accordance with the sheet width, to receive the sheet in the plane of movement past said coating roller; a sprocket rotatable with each conveyor roller; a chain engaged with said sprockets; a drive member engaged with said chain to rotate said conveyor rollers; driving means; and a universal driving device between said driving means and said drive member to accommodate vertical adjustment of said conveyor.

7. In apparatus for applying a coating to one surface of a sheet of material, a rotatable coating roller arranged to engage such surface and apply a coating thereto; mechanism for feeding the sheet into engagement with said coating roller; first means in advance of said roller arranged to engage the other surface of the sheet to press such one surface against said roller during passage of the forward portion of the sheet in contact with said roller; retractable second means

rearward of said roller normally maintained out of the plane of said sheet and displaceable into engagement with the other surface of the sheet to press such one surface against said roller during passage of the rearward portion of the sheet in contact with said roller; an air cylinder and piston device operable, when actuated, to move said second pressure roller between the sheet engaging position and a retracted position; and a photo-electric scanning device having a beam in the path of the sheets and operatively connected with said mechanism and effective, by interruption of its beam when the leading edge of the sheet approaches said first means, to activate said device to retract said second means and, in clearance of its beam when the trailing edge of the sheet approaches said first means, to engage said second means with the sheet.

8. In apparatus for applying a coating to one surface of a sheet of material, a rotatable coating roller arranged to engage such surface and apply a coating thereto; mechanism for feeding the sheet into engagement with said coating roller; a first pressure roller in advance of said coating roller arranged to engage the other surface of the sheet to press such one surface against said coating roller to coat the same; a retractable second pressure roller rearwardly of said coating roller normally maintained out of the plane of said sheet and displaceable into en-

gagement with the other surface of the sheet to press such one surface against said coating roller to coat the same; an air cylinder and piston device operable, when actuated, to move said second pressure roller between the sheet engaging position and a retracted position; and a photo-electric scanning device having a beam in the path of the sheets and operatively connected with said mechanism and effective, by interruption of its beam when the leading edge of the sheet approaches said first pressure roller, to activate said device to retract said second pressure roller and, when the trailing edge of the sheet approaches said first pressure roller, to engage said second pressure roller with the sheet.
